DIFFERENTIAL-PRESSURE GAGE.

1,006,100.

Specification of Letters Patent. Patented Oct. 17, 1911.

Application filed April 25, 1910. Serial No. 557,381.

To all whom it may concern:

Be it known that we, WALTER GEORGE KENT and JOHN LAWRENCE HODGSON, subjects of the King of Great Britain, residing 5 at London, W. C., have invented certain new and useful Improvements in Differential-Pressure Gages, of which the following is a specification, reference being had therein to the accompanying drawing.

10 This invention relates to gages adapted to be controlled by the difference between two pressures, and the object of the invention is to provide a gage of this type which shall be very sensitive to a small difference of 15 pressure, less sensitive to a large difference of pressure, and incapable of being damaged by an overload or excess of difference of pressures.

With these and other objects in view, the 20 invention consists of certain novel features of construction, as will be more fully described and particularly pointed out in the appended claims.

The accompanying drawing is a side elevation, partly in section, of so much of an apparatus embodying our invention as is necessary to understand the same.

The principal features of the device are 25 inclosed in a casing C, said casing forming also, as will be hereinafter explained, an essential part of the invention. The casing is connected by two pipes P' and P² with a conduit H through which a fluid is supposed to be passing. This conduit is shown 30 as what is known as a Venturi tube such device being well known in connection with fluid meters. The pipe P² connects with the throat of the Venturi tube, while the pipe P' connects with the up-stream portion of 35 the tube or that portion from which the fluid is approaching the throat. As is well known in connection with such Venturi tubes, the pressure at the point where the pipe P' is connected is greater than the pressure 40 at the throat where the pipe P² is connected. Therefore the pressure inside of the casing C is greater than the pressure in the spaces between the disks which we will now proceed to describe.

45 In the simplest form of the invention the gage might consist of a single pair of corrugated disks or diaphragms J J', but in the preferred embodiment illustrated we have shown five of such pairs of disks, two being 50 illustrated in section and three in side elevation. The lower disk of each pair has its

outer edge or flange bent over and crimped upon the outer edge of the upper disk of the pair as indicated at 1. In the center of each pair of disks and inside thereof are two 55 thickened and relatively stiff center pieces j j', the upper one of each pair of center pieces having a threaded nipple 2 to engage a threaded hole 3 in the lower center piece of the next pair of disks above it. The nipple, however, of the uppermost center piece j enters a cap 4, while the lower center piece j' of the lowermost pair of disks is coupled, as by a threaded nipple 5, with an opening 60 in the bottom of the casing C with which 65 opening the pipe P² communicates.

To effect tight joints between the different pairs of disks or diaphragms we interpose washers j², there being also a similar washer 70 below the lowermost pair of disks.

75 Through an opening in the cap 4 a rod or wire J³ extends, said rod or wire having a head at its lower end inside of the cap. Said rod or wire J³ leads through gland J⁴ to the point or device where the accumulated 80 motion resulting from expansion or contraction of the several pairs of disks will be transmitted to a suitable device which may be a pointer p coöperating with a scale S to indicate the conditions of expansion or contraction of the pair or pairs of diaphragms 85 due to variations of the pressure inside and outside of said pairs of diaphragms.

The casing is pressure tight, and to said 90 casing is led the fluid from the main, while the pressure from the throat is conveyed to the interior of the diaphragms. Owing to the fact that the structure is such that the greater pressure is outside of the diaphragms, any excess of such outside pressure 95 will only serve to collapse the diaphragms until the center pieces j and j' contact with each other in the manner illustrated in the drawing after which any further increase of outside pressure can have 100 no effect upon the diaphragms and consequently they cannot be damaged by overload of excess pressure. Initially there is a gap 105 between the center pieces j and j', and the disks of each pair are in contact only around their peripheries. As the load is put on, the diaphragms approach each other, their motion being resisted by the pull of the wire J³. As the pressure increases, the disks begin to close together from their circumference or 110 margin inwardly so that the area of unsupported disks exposed to the pressure

gradually diminishes. This is due to the fact that the disks or walls of the chambers are in contact at their margins and are nearly parallel from said margins inwardly. 5 Finally when the maximum difference of pressure is reached, the disks and the center pieces contact, and no further increase of the difference of pressure can cause further motion.

10 It is to be understood that we do not limit ourselves to a plurality of pairs of disks or diaphragms, since the invention in its simplest form might embody only a single pair. But owing to the structure illustrated 15 and described, the capacity can be increased to any amount by increasing the number of pairs of disks which are connected together by the nipples and threaded holes of the center pieces. It is also to be understood 20 that we do not limit ourselves to the scale and pointer employed for indicating the results of the operation of the gage, since any other device that may be desired may be substituted for the scale *S* and pointer *p*.

25 Having thus described our invention, what we claim is:

1. A device for measuring the difference of two fluid pressures consisting of a closed casing subjected to the greater pressure and 30 containing a second casing having flexible walls subjected to the lesser pressure, the flexible walls being connected at their mar-

gins and arranged to contact against each other as the difference of pressure increases, said contact progressing continuously from the outer edge toward the center, whereby the increased external pressure will cause the contacting walls to support each other to prevent permanent distortion, and an exhibitor actuated by the movement of said 40 flexible walls.

2. A device of the character described comprising a casing, means for supplying fluid under pressure thereto, flexible diaphragms supported in said casing and united at their margins, means for introducing fluid under pressure between said diaphragms, the walls of said diaphragms being adapted to contact continuously from their margins inwardly when the external pressure is greater than the internal pressure, whereby said excess external pressure will cause the contacting portions of said diaphragms to support each other to prevent permanent distortion, and an exhibitor connected to said diaphragms.

In testimony whereof we affix our signatures in presence of two witnesses.

WALTER GEORGE KENT.
JOHN LAWRENCE HODGSON.
